UNITED STATES PATENT OFFICE.

ROBERT B. BRUNSWICK, OF PHILADELPHIA, PENNSYLVANIA.

BOTTLE-OPENER.

1,129,952.

Specification of Letters Patent.

Patented Mar. 2, 1915.

Application filed May 8, 1914. Serial No. 837,191.

To all whom it may concern:

Be it known that I, ROBERT B. BRUNSWICK, a citizen of the United States, residing at Philadelphia, in the county of Philadelphia and State of Pennsylvania, have invented a new and useful Bottle-Opener; and I do hereby declare the following to be a full, clear, and exact description of the invention, such as will enable others skilled in the art to which it appertains to make and use the same.

This invention relates to a new and useful improved bottle opener, having for one of its objects to provide an opener terminating at one end in a tubular member constituting a holder for a pen or a pencil, whereby the pencil may always be held in position ready for use.

Another object of the invention is to construct an opener having simple and efficient features of construction, one of which is to construct the opener from a single piece of wire, the end portions of which are brought together and welded together and within one end of a tubular member, which forms a holder for a pencil or a pen. Portions of the wire adjacent the extreme end portions being struck up or swaged to form ears to engage under the bottle cap.

The details of construction may be subjected to alterations, falling within the scope of what is claimed.

The invention comprises further features and combinations of parts, as hereinafter set forth, shown in the drawings and claimed.

In the drawings: Figure 1 is a view of the bottle opener shown in a position, in readiness for removing the cap of the bottle. Fig. 2 is an enlarged detail view of the opener. Fig. 3 is a sectional view. Fig. 4 is a sectional view on line 4—4 of Fig. 3. Fig. 5 is a longitudinal sectional view show-

ing another form of construction. Fig. 6 is a sectional view on line 6—6 of Fig. 5.

Referring more particularly to the drawings, 1 designates a bottle opener as a whole, which in Figs. 1 to 5 inclusive comprises a body portion having two diverging side members 3 terminating in curved portions 4, which are connected by the transverse parts 6. The diverging parts are provided with struck up or stretched portion 7, designed to engage under the periphery 8 of a bottle cap 9 for removing the same. The other end of the body portion terminates in a tubular member 10, designed to receive a pen, pencil or the like for the purpose hereinbefore stated.

In Figs. 5 and 6 the diverging portions are brought together in parallel relation as shown at 11 and partly welded together at 12, and also welded within the tubular member as shown at 13, a portion of the tubular member being depressed from opposite sides in between the parallel parts.

The invention having been set forth, what is claimed as new and useful is:—

A connector for a bottle opening tool and handle therefor comprising a hollow tubular member having unobstructed exterior and interior surfaces, and in one end of which two adjacent parallel parts of the tool are permanently secured for holding the two parts together to prevent spreading of said parts, the other end of said member being adapted to receive either the used end, or the non-used end of another tool which is adapted to constitute a handle.

In testimony whereof I have signed my name to this specification in the presence of two subscribing witnesses.

ROBERT B. BRUNSWICK.
